W. E. Smith

ATTORNEY.

UNITED STATES PATENT OFFICE.

SAMUEL R. FRY, OF WYOMISSING, PENNSYLVANIA, ASSIGNOR TO THE NARROW FABRIC CO., OF WEST READING, PENNSYLVANIA, A CORPORATION OF PENNSYLVANIA.

COAT HANGER.

Application filed February 16, 1925. Serial No. 9,484.

The object of my invention is to provide an improved fabric-covered coat-hanger in which the essential bar element will be tightly and securely enclosed in an ornamental and useful fabric covering applied at small cost; and it is fully set forth in connection with the accompanying drawings and clearly defined in the claim.

Fig. 1 shows an ordinary coat hanger bar 10 fabric-covered in accordance with my invention; part of the covering being broken away to show the uncovered bar with its end portion shown in longitudinal section.

Fig. 2 shows the tubularly braided covering fabric loosely strung upon the hanger bar and secured to one end thereof, preliminary to stretching the same longitudinally as indicated by the dotted lines.

Fig. 3 shows one end of the hanger bar 20 in enlarged longitudinal section and with the projected end of the fabric-covering in-turned and secured in the recessed end of the bar; an end view of the latter being shown in Fig. 4.

The hanger bar 5 is indicated in well-known simple form, as a mere curved strip of wood to which a suspending hook 6 is secured midway of its length; said hook being secured thereto after the fabric-covering has been applied to the bar as hereinafter set forth. To provide for securing said covering to the bar, each end of the latter is shown as provided with a central longitudinal recess 7 in which the in-turned 35 projecting end of the fabric is suitably held.

My invention provides for employing a piece of tubularly braided fabric 10 as a covering material; this being made of less length than is adapted to normally cover the hanger bar, but with a cross-sectional periphery sufficiently greater than that of the bar to provide, first, for its being easily strung upon the bar; and second, for its being longitudinally stretchable, as its 40 braided structure readily permits, so as to provide inturnable extending material 10^a, 10^b, beyond the opposite ends of the bar when the stretching action has contracted the tubular form of the braided fabric so as

to cause it to closely hug the enclosed bar. 50 Thus, as indicated in Fig. 2, the loosely strung braided fabric 10 may have one end 10^a thereof inturned into one of the end-wise bar recesses 7, with the tucked-in portion suitably secured in the latter; and be 55 thereafter stretched horizontally, as indicated by the dotted lines 10^b, until the whole length of the bar is tightly hugged thereby and its free end 10^a extends beyond the opposite end of the bar so as to enable its being 60 similarly inturned and secured in the second end recess 7. As shown the tucked-in end fabric is very firmly secured by a clamping 65 plug 15 employed with or without a suitable cement, but obviously either of such securing means, or other as preferred, may be employed for locking the inturned material so as to practically prevent loosening of the longitudinally stretched fabric.

The tubular braided fabric may be 70 cheaply produced in continuous length of determined greater normal interior periphery than that of the hanger bar to be covered, and be readily cut to the correspondingly reduced lengths required for 75 providing inturning extensions 10^a, 10^b, of proper length when the body of the braid is made to tightly hug the bar; so that the mere securing of these extending ends of the horizontally stretched and diametrically contracted tubular fabric substantially as set forth, will insure the securing of a very 80 tightly and satisfactorily covered bar with great economy of production.

What I claim is:

The method of covering a coat-hanger bar or the like which consists, first in loosely stringing thereon a tubularly-braided fabric having a normally greater periphery than the bar, second in longitudinally stretching said fabric to tightly close the same upon the bar and provide extending end portions, and third in inturning said extending end portions and securing the same to the ends of the bar.

In testimony whereof I affix my signature.

SAMUEL R. FRY,
